ATTORNEYS

UNITED STATES PATENT OFFICE.

FAIRLEIGH S. DICKINSON, OF RUTHERFORD, NEW JERSEY.

SYRINGE.

1,142,682.

Specification of Letters Patent.

Patented June 8, 1915.

Application filed October 27, 1914. Serial No. 868,811.

To all whom it may concern:

Be it known that I, FAIRLEIGH S. DICKINSON, a citizen of the United States, and a resident of Rutherford, in the county of Bergen and State of New Jersey, have invented new and useful Improvements in Syringes, of which the following is a full, clear, and exact description.

The object of the invention is to provide certain new and useful improvements in 10 syringes and like devices whereby the plunger is held against accidental dropping out of the barrel when pointing the nozzle upward.

In order to accomplish the desired result, use is made of a clip adapted to engage the barrel and a spring arm extending from the said clip and ranging lengthwise of the 20 syringe, the arm extending beyond the rear end of the clip and being bent inward so that its free end bears against the outside of the plunger of the syringe to hold the said plunger against accidental movement in the barrel.

A practical embodiment of the invention 25 is represented in the accompanying drawings forming a part of this specification, in which similar characters of reference indicate corresponding parts in all the views.

Figure 1 is a side elevation of a syringe 30 provided with the combined finger piece and retaining device; Fig. 2 is a cross section of the same on the line 2—2 of Fig. 3; Fig. 3 is a sectional side elevation of the combined 35 finger piece and retaining device in position on the syringe; Fig. 4 is a perspective view of the finger piece and the retaining device; Fig. 5 is a side elevation of a syringe provided with a modified form of the finger 40 piece and retaining device; Fig. 6 is a plan view of the combined finger piece and retaining device; and Fig. 7 is a sectional side elevation of the same.

In syringes, especially those made of glass, 45 as now generally constructed the plunger is liable to drop out of the barrel when pointing the nozzle thereof in an upward direction, and hence the plunger is liable to be broken, injured or soiled, so as to render the 50 syringe unfit for use. In order to prevent the plunger from accidentally dropping out of the barrel, use is made of a clip engaging the barrel and a plunger retaining device held on the clip and adapted to engage the 55 plunger with sufficient force to hold the plunger against accidental movement but to allow

the user to reciprocate the plunger in the barrel for drawing in liquid or forcing it out in the usual manner.

The syringe on which the device is applied 60 consists of the usual barrel A, terminating at its outer end in a nozzle A' and provided at its inner end with an exterior collar A². In the barrel A reciprocates a plunger B provided at its outer end with a suitable 65 handle B', to permit the user to conveniently reciprocate the plunger in the barrel A for drawing in or ejecting liquid in the usual manner. A ring C fits exteriorly on the barrel A and abuts against the collar A², 70 and the said ring C is provided at opposite sides with finger pieces D, D' extending outwardly in opposite directions to permit the user to take hold of the finger pieces with the fore and middle fingers at the time of 75 pressing the plunger B inward with the thumb for ejecting the liquid from the barrel in the usual manner. To the ring C is secured a clip in the form of a narrow ring E provided with a number of prongs E' 80 engaging the exterior surface of the barrel A so as to hold the ring C and with it the finger pieces D, D' in position on the barrel. One of the prongs E' is provided with a 85 spring arm F which extends rearwardly through a guideway G in the form of a slot formed in the rings E and C and in the finger piece D'. The free end F' of the spring arm F projects a distance beyond the collar A² and is bent inwardly to bear against 90 the exterior surface of the plunger B with sufficient force to hold the plunger B against accidental movement in the barrel A. It will be noticed that by the arrangement described a comparatively long spring arm F 95 is provided to furnish the resiliency required to hold the plunger B against accidental movement in the barrel A. By passing the spring arm F through the guideway G, the spring arm is protected against accidental 100 injury when using the device, as above explained, as the spring arm readily yields when passing over the collar A² at the time of placing the device in position on the barrel A.

In the modified form shown in Figs. 5, 6 and 7 the ring C' is provided with the finger pieces D², D³ and with a split clip band E² partly encircling the barrel A, as plainly shown in Fig. 5. One free end of the clip 110 band E² terminates in a spring arm F² which extends rearwardly over the ring C' and the

collar A², and the free end F² of this spring arm F² is bent inwardly and bears against the exterior surface of the plunger B to hold the latter against accidental movement in the barrel A.

Having thus described my invention, I claim as new and desire to secure by Letters Patent:

1. A syringe attachment, comprising a ring 10 adapted to engage the barrel of a syringe at the rear end and provided with a member extending lengthwise of the barrel, and a spring arm extending from the extremity of said member and ranging lengthwise of the 15 syringe, the arm extending back to and beyond the ring and the free end of the arm being adapted to bear against the outside of the syringe plunger to hold the latter against accidental movement in the barrel.
2. A syringe attachment, comprising a ring 20 provided with finger pieces and adapted to encircle the barrel, the ring being adapted to abut against the collar on the rear end of the barrel, a clip member extending from the 25 said ring lengthwise of the barrel and bearing on the exterior of the barrel, and a spring arm integral at one end with the extremity

of said clip member and extending back to and beyond the ring, the free end of the said arm extending inwardly and being adapted 30 to bear against the outside of the syringe plunger.

3. A syringe attachment, comprising a ring provided with finger pieces and adapted to encircle the barrel, the ring being adapted to 35 abut against the collar on the rear end of the barrel, a clip member extending from the said ring lengthwise of the barrel and bearing on the exterior of the barrel, and a spring arm integral at one end with the said clip 40 member and extending back to and beyond the ring, the said ring and one of the said finger pieces being provided with a guide-way for the said arm, the free end of the arm extending back to and beyond the ring 45 and being bent inward to bear exteriorly on the syringe plunger.

In testimony whereof I have signed my name to this specification in the presence of two subscribing witnesses.

FAIRLEIGH S. DICKINSON.
